United States Patent [19]
Gamm

[11] **Patent Number:** **Des. 281,734**
[45] **Date of Patent:** **** Dec. 17, 1985**

[54] **STRAP POCKETED SHOE**

[75] **Inventor:** **Robert J. Gamm, St. Louis County, Mo.**

[73] **Assignee:** **Kangaroos U.S.A., Inc., St. Louis, Mo.**

[**] **Term:** **14 Years**

[21] **Appl. No.:** **510,562**

[22] **Filed:** **Jul. 5, 1983**

Related U.S. Application Data

[63] Continuation-in-part of Ser. No. 436,562, Oct. 25, 1982.
